ATTORNEY:

UNITED STATES PATENT OFFICE.

JOHN WESLEY BLODGETT, OF NASHVILLE, TENNESSEE.

IMPROVEMENT IN ROTARY ENGINES.

Specification forming part of Letters Patent No. 170,512, dated November 30, 1875; application filed March 30, 1875.

To all whom it may concern:

Be it known that I, J. W. BLODGETT, of Nashville, in the county of Davidson and State of Tennessee, have invented certain new and useful Improvements in Rotary Engines; and I do hereby declare that the following is a full, clear, and exact description thereof, reference being had to the accompanying drawings and to the letters of reference marked thereon, which forms part of this specification.

The nature of my invention consists in the construction and arrangement of a rotary engine, as will be hereinafter more fully set forth.

In order to enable others skilled in the art to which my invention appertains to make and use the same, I will now proceed to describe its construction and operation, referring to the annexed drawing, in which—

Figure 1 is a central vertical section on line $x x$, Fig. 3. Figs. 2 and 3 are end views, and Fig. 4 is a view of the double cut-off wheel J.

A and B represent two cylinders, of suitable unequal diameter, of the same length, placed one on top of the other, and connected or communicating with each other, as shown. This double cylinder A B is, by two partitions, $a a$, divided into a central cut-off chamber, and two driving-chambers, one on each side of the central chamber. The partitions a are slipped into the cylinder, one from each end, and bear against shoulders formed around the interior of the cylinder. The three chambers thus formed are provided with water-cocks b , to draw the water from the same. In each partition a is a port, x , through which ports the steam is supplied alternately in each end of the double cylinder. Within the central or cut-off chamber of the double cylinder is a rotary cut-off wheel, C, secured on a shaft, d , passing longitudinally through the center of the cylinder A. This cut-off wheel is constructed, as shown in the drawing, with a concentric passage, e , on one side, near the periphery, half-way round, and a similar passage, e' , on the other side, around the other half, so as to change the steam alternately in the driving-chambers. D is the steam-inlet pipe, entering the central cut-off chamber, and E is the exhaust-pipe, communicating with the inner ends of both the driving-chambers. On the shaft d , in each of the driving-chambers, is secured a driving-cylinder,

G, which is cast hollow, with a V-shaped flange or wing, h , running longitudinally on one side of it. The opposite side of the driving-cylinder from the flange h is made thicker, as shown at i , to balance the flange. In the part B of the main cylinder, over each driving-cylinder G, is another cylinder, H, provided with a groove, f , corresponding in size with the flange h , and on the side where this groove is the cylinder H is made thicker, so as to balance the opposite side. The cylinders G H run close together, so that the steam cannot pass between them, and they pass each other by the flange or wing h entering the groove f . The two cylinders are carried around at the same speed by means of two cog-wheels, I I, of equal size, placed one on the shaft d , and the other on the shaft d' of the cylinders H. These cog-wheels may be on the outside of the casing A B, or within a chamber formed at one end thereof. The shaft d passes through a steam-tight boxing at each end of the casing A B, said boxing consisting of two cones, m and n , bored out so that one exactly fits in the other. The cone m is cast on the head of the casing, while the cone n is screwed on the shaft d till it fits steam-tight over the cone m , and is held there by means of a nut, p . This does away with the usual stuffing-box, and keeps all the driving-power in the center of the engine.

The cut-off wheel C, above described, is for engines which are not intended to be run backward. For engines that require to be run in both directions a double cut-off wheel, J, is used, and in this case each partition a must be provided with two steam-ports x .

Having thus fully described my invention what I claim as new, and desire to secure by Letters Patent, is—

The combination of the central cut-off wheel C, with its steam-passages $e e'$, and cylinders G G and H H, arranged in the casing A B, having two interior partitions, $a a$, all constructed and arranged to operate substantially as and for the purposes herein set forth.

In testimony that I claim the foregoing as my own I affix my signature in presence of two witnesses.

J. W. BLODGETT.
